Primary Examiner — Mary Ann Calabrese*Assistant Examiner* — Catherine Ho(74) *Attorney, Agent, or Firm* — Fox Rothschild LLP(57) **CLAIM**

The ornamental designs for a cash register, as shown and described.

DESCRIPTION

FIG. 1 is a perspective view of a cash register of the present invention.

FIG. 2 is a bottom view of the cash register.

FIG. 3 is a top view of the cash register; and,

FIG. 4 is a left side view of the cash register.

The broken lines depict portions of a cash register that form no part of the claim.

1 Claim, 4 Drawing Sheets(56)
